J. G. Treadwell

UNITED STATES PATENT OFFICE.

JOHN G. TREADWELL, OF ALBANY, NEW YORK.

STOVE.

Specification of Letters Patent No. 26,308, dated November 29, 1859.

To all whom it may concern:

Be it known that I, JNO. G. TREADWELL, of the city and county of Albany and State of New York, have invented certain new and 5 useful Improvements in Ventilating-Stoves, of which the following is a full, clear, and exact description, reference being had to the accompanying drawings, forming part of this specification, in which—

10 Figure 1 represents a vertical section of a stove and pipe embracing my improvements. Fig. 2 represents a side elevation of the same. Fig. 3 represents a plan of the pipe and ventilating flue.

15 The nature of my invention consists in casting a ventilating flue immediately under and in contact with the bottom of the stove, which communicates at the rear of the stove with a vertical flue passing up through the 20 smoke pipe and entering the chimney, thus creating an independent ventilating draft from the room.

In the accompanying drawings A represents the cylindrical frame and bottom of a 25 stove usually constructed of cast iron. On the bottom of this stove the horizontal ventilating flue B is formed, and communicates with the vertical flue D at the rear of the stove. The ventilating flue B when cast 30 with the frame or bottom of the stove, may be formed with an elbow at its rear end on which to fit the vertical flue D which is usually manufactured of sheet iron.

The flue B, from its close contact with the 35 stove is thoroughly heated and the air as it enters is rarefied and passes up through the

flue B, which, passing up through the center of the smoke pipe C, is surrounded by the heat within it, so that the rarefaction of the air is continued throughout the entire passage of the flues, and thus a strong and free draft is created to ventilate the room. The mouth of the flue B is provided with a door or valve F, so that the ventilating draft may be regulated at pleasure. When the draft of 45 the stove is shut off, the ventilating draft accelerates the cooling of the stove. The ventilating draft being entirely independent of, and regulated without affecting the stove draft, the ventilation of the room may be 50 regulated as circumstances require.

A recess E is formed in the rear of the stove and through this recess the smoke pipe C communicates with the stove and establishes a draft from the fire, the hot air and 55 smoke completely surrounding the flue which passes up through the pipe, and keeping it continually hot.

Having thus fully described my invention what I claim as new and desire to secure by 60 Letters Patent is—

The arrangement of the stove A, flue B, door F, flue D, and smoke pipe C, where the flue B, is secured to or made a part of the underside, or bottom of the stove, the several 65 parts being connected and constructed, substantially as and for the purpose specified.

JNO. G. TREADWELL.
